UNITED STATES PATENT OFFICE.

JAMES THOMAS ROBERTS, OF ANDERSON, SOUTH CAROLINA.

FABRIC-TUFTING MACHINE.

SPECIFICATION forming part of Letters Patent No. 739,447, dated September 22, 1903.

Application filed July 7, 1902. Serial No. 114,671. (No model.)

To all whom it may concern:

Be it known that I, JAMES THOMAS ROBERTS, a citizen of the United States, residing at Anderson, in the county of Anderson and State of South Carolina, have invented a new and useful Fabric-Tufting Machine, of which the following is a specification.

This invention relates to certain improvements in fabric-tufting machines of that class shown in Letters Patent granted to me on September 12, 1899, No. 632,927.

One of the objects of the invention is to provide an improved form of joint for connecting the two hand members or sections of the implement in such manner as to accurately guide them one on the other and prevent any lateral play such as might tend to alter the relative positions of the needle and loop-holder.

A further object is to cheapen the construction and to provide a convenient means of adjusting the stroke of the needle.

A still further object of the invention is to provide an improved form of adjustable loop-holder and its operating-spring.

With these and other objects in view the invention consists in the novel construction and arrangement of parts hereinafter described, illustrated in the accompanying drawings, and particularly pointed out in the appended claims.

In the drawings, Figure 1 is a sectional plan view of a fabric-tufting implement constructed in accordance with my invention.

Fig. 2 is a perspective view illustrating the two members or sections of the device detached. Fig. 3 is a transverse sectional elevation of a portion of the implement on the line 3-3 of Fig. 1. Fig. 4 is a detail perspective view of the loop-holding spring detached.

Similar numerals of reference are employed to indicate corresponding parts throughout the several figures of the drawings.

The device comprises two opposite members 5 and 6, the former carrying a needle 7 and the latter a loop-holding device 8. Each of the handpieces is of such shape as to be conveniently grasped by the operator, suitable finger-openings 9 being arranged in each member.

To the inner surface of the needle member 5 is secured a rib or tenon 10, having under-

cut shoulders 11, as indicated more clearly in Figs. 2 and 3. The widened inner portion of the rib is of comparatively short length, the 55 rib being extended in the form of a narrow strip to the extreme end of the section. On the inner face of the section 5 is a groove 12 for the reception of a shank portion of a needle 13, the latter being of the usual shape 60 and provided with a widened shank in which are formed two openings for the passage of securing-bolts 14, which extend through openings 15 in the handpiece 5 and are provided with securing-nuts 16 for retaining 65 them in proper position. In the handpiece are formed a number of openings 15, through which the bolts may be adjusted in order to allow the needle-point to extend to a greater or less distance beyond the end of the handpiece. The inner face of the handpiece 5 is further provided with a pair of parallel grooves 17, extending from the forward end of the rib 10 to the front end of the handpiece and arranged one on each side of the 70 needle-receiving groove 12.

The inner face of the loop-holding carrier 6 is substantially flat, and to said face is secured a strip 18, preferably formed of wood of somewhat harder or better wearing quality 80 than the cheaper material of which the body portion of the handpieces may be formed, although, if necessary, this strip may be of the same material as the handpiece or may be formed integral therewith. From a point 85 near the front end of the handpiece the strip 18 is divided into two ribs 19 by a centrally-disposed longitudinal slot 20, extending to the rear end of the strip, the walls of the slots being undercut, as indicated at 22, to receive 90 the widened portion of the rib or tenon 10, while the upper portion of the slot is of a width just sufficient to receive the narrower or base portion of said rib. In the face of the strip at a point in advance of the forward 95 end of the slot are two lugs or pins 23, which, when the two handpieces are assembled, fit within the parallel grooves 17 and serve to positively prevent any independent lateral movement of either of said handpieces, while at the rear and body portions of the handpieces independent movement is prevented by the closely-fitting rib and groove, and the two pieces are held together by the passage of

the wider portion of the rib into the undercut portions 22 of the groove.

The forward end of the strip 18 is slotted, as indicated at 25, and the adjacent face of 5 the handpiece is provided with an alining recess 26 for the reception of a leaf-spring 27, having an inherent tendency to move in the direction of the needle. The rear end of the spring is confined in place by bolt 28, and its 10 forward end is provided with a notch 29 to receive the curved or angular face of the loop-holder 8. The loop-holder is of the usual construction, being provided with a longitudinally-grooved inner face for the reception 15 of the needle, and at its rear end is provided with an eye 30, through which may pass a pivot-pin 31, said pivot-pin being adapted to fit in any one of a number of openings 32, formed in the strip 18, in order that the distance 20 which the end of the loop-holder projects beyond the end of the handpiece may be properly adjusted. The spring is relatively stationary and possesses sufficient resiliency to properly act on the loop-holder without 25 regard to the pivotal point of the latter.

In assembling the two hand members the forward end of the rib 10 may be readily inserted into the rear end of the undercut slot 20, and as the two members are drawn together 30 the lugs or pins 23 will be guided into the parallel grooves 17 and the parts thus firmly held together. The forward limit of movement of the needle-carrier 5 is determined by the forward end of the rib 10 and the end 35 wall of the groove 20, while the rearward limit of movement is determined by an adjustable pin 33, adapted to any one of a number of openings 34, formed in the two walls of the slot 20, said pin being engaged by the rear 40 end of the widened portion of the rib 10 with said pin. Any suitable number of openings 34 are provided in order that the stroke may be adjusted for the formation of loops of any desired length.

45 The implement is operated in the well-known manner for the formation of loops of yarn or other material on a fabric base.

While the construction herein described,

and illustrated in the accompanying drawings, is the preferred form of the device, it 50 is obvious that various changes in the form, proportions, size, and minor details of the structure may be made without departing from the spirit or sacrificing any of the advantages of the invention.

Having thus described the invention, what I claim is—

1. The combination in a tufting implement, of the two hand members having interengaging ribs and grooves, and one of said members being provided with a looper-receiving recess at one end and with openings extending through the side walls of the recess, a pin adjustable to any one of said openings, a looper pivoted on said pin, an auxiliary spring seated 60 within the recess and having at its outer end a notch for the reception of the rear face of the looper to thereby assist in holding the looper from lateral movement, and a needle carried by the opposite member.

2. The combination in a tufting implement, of the two hand members, an adjustable needle carried by one member, an adjustable looper carried by the second member, one of said members having an elongated slot or 75 groove provided with undercut walls, a rib extending from the face of the opposite member, said rib fitting within the groove and having a widened portion fitting within the undercut walls of the groove, and means for preventing independent lateral play of said members at points adjacent to the needle and looper, said means comprising a pair of grooves formed in the face of one member and extending forwardly on opposite sides of 80 the base portion of the needle, and pins carried by the opposite member and fitting within said grooves, substantially as specified.

In testimony that I claim the foregoing as my own I have hereto affixed my signature in 90 the presence of two witnesses.

JAMES THOMAS ROBERTS.
